(57) **CLAIM**

The ornamental design for a chopping block for splitting logs as shown and described.

DESCRIPTION

FIG. 1 is a front perspective view of a chopping block for splitting logs.

FIG. 2 is a front perspective view of the chopping block for splitting logs in an exploded arrangement.

FIG. 3 is a front elevation view of the chopping block for splitting logs in the exploded arrangement.

FIG. 4 is a left side elevation view of the chopping block for splitting logs in the exploded arrangement.

FIG. 5 is a back elevation view of the chopping block for splitting logs in the exploded arrangement.

FIG. 6 is a right side elevation view of the chopping block for splitting logs in the exploded arrangement.

FIG. 7 is a top plan view of the chopping block for splitting logs in the exploded arrangement.

FIG. 8 is a bottom plan view of the chopping block for splitting logs in the exploded arrangement.

FIG. 9 is a front perspective view of another chopping block for splitting logs.

FIG. 10 is a front perspective view of the chopping block for splitting logs of FIG. 9 in an exploded arrangement.

FIG. 11 is a front elevation view of the chopping block for splitting logs of FIG. 9 in the exploded arrangement.

FIG. 12 is a left side elevation view of the chopping block for splitting logs of FIG. 9 in the exploded arrangement.

FIG. 13 is a back elevation view of the chopping block for splitting logs of FIG. 9 in the exploded arrangement.

FIG. 14 is a right side elevation view of the chopping block for splitting logs of FIG. 9 in the exploded arrangement.

FIG. 15 is a top plan view of the chopping block for splitting logs of FIG. 9 in the exploded arrangement; and,

FIG. 16 is a bottom plan view of the chopping block for splitting logs of FIG. 9 in the exploded arrangement.

The broken lines in the figures represent portions of the article that form no part of the claimed design.
